UNITED STATES PATENT OFFICE.

WILLIAM C. ROBINSON, OF SEWICKLEY, AND HOMER G. KNODERER, OF EDGEWORTH, PENNSYLVANIA, ASSIGNEES TO NATIONAL METAL MOLDING COMPANY, OF PITTSBURGH, PENNSYLVANIA, A CORPORATION OF PENNSYLVANIA.

METAL MOLDING.

1,287,108.

Specification of Letters Patent. Patented Dec. 10, 1918.

Application filed May 12, 1917. Serial No. 168,171.

To all whom it may concern:

Be it known that we, WILLIAM C. ROBINSON, residing at Sewickley, in the county of Allegheny and State of Pennsylvania, and 5 HOMER G. KNODERER, residing at Edgeworth, in the county of Allegheny and State of Pennsylvania, both citizens of the United States, have invented or discovered certain new and useful Improvements in Metal 10 Moldings, of which improvements the following is a specification.

The invention described herein relates to electrical conductor conduits, and has particularly to do with conduits known as metal 15 moldings which are usually applied to the surface of walls or other supports either for original installations or for the extension of circuits from conductors carried in inner-wall conduits.

20 The metal molding contemplated herein may be considered as consisting of two elements, namely, conduits and conduit fittings. There are in general two types of conduits, those formed of a single piece of 25 metal and which are usually substantially elliptical, and those formed in two parts, a base and a cap, suitably held together. In making installations of two-part conduits, one part, usually the base, may be secured 30 to the supporting surface, after which the electrical conductors may be laid therein and the cap then applied; or the cap and base may be first assembled and the conductors fished through them. The present 35 invention contemplates both one and two-piece conduits regardless of their intended manner of installation.

The conduit fittings, the second of the above named elements of metal molding, 40 include all forms of members for connecting the conduit to junction or outlet boxes, sockets, switches, etc., or for connecting the conduits to each other such as butt-joints, elbows, T's, crosses, etc. As actually manufactured these fittings are usually, if not always, made of two parts, a base and a cap, adapted, when assembled, to be either directly or indirectly connected to each other,

and the present invention contemplates all such two-part fittings.

One of the essential requirements of an installation of metal molding is that the conduits and fittings be so connected to each other as to afford a path of electrical conductivity from the remotest point of the 55 molding to the ground, so that, in case of conductor trouble, the current may be grounded. In two-part conduits it is usually required that this path of conductivity be established through the conduit and fitting bases; accordingly the terms "conduit base" or "fitting base", as they hereinafter appear in the specification and claims, are used to designate those parts of the conduits and fittings that are electrically connected to 60 each other for the purpose described, and this quite irrespective of the configuration of the parts or their intended manner of assembly.

Various types and constructions of electrical and mechanical connections have been provided for attaching the conduits to the fittings, but, as far as is known, not metal molding has been provided wherein the establishment of proper electrical connections has been made a requisite to the complete mechanical assembly and connection of all the necessary parts of the molding. That is to say, in the installation of molding heretofore provided, a careless or indifferent 70 workman may, as by cutting the conduit sections too short or by other acts or omissions, completely assemble all the essential parts of conduits and fittings without having established an adequate electrical bond 75 at each point of connection, and frequently such a condition cannot be detected after the installation is completed. Accordingly, the principal object of the present invention is to provide metal molding which cannot be 80 adequately or completely assembled until adequately electrical connections have been established between the conduits and fittings.

85 A further and more specific object of the invention is to provide metal molding characterized as just stated, and wherein the

- mechanical and electrical connections between conduits and fittings are effected by laterally applicable snap connecting and bonding members.
- 5 A still further object is to provide such metal molding conduits, and fittings wherein the conduits need not be cut to precise lengths, and wherein both one and two-piece conduits may be used interchangeably 10 with the fittings.

In the accompanying sheets of drawings forming part of our specification we have illustrated the preferred embodiment of our invention. Figure 1 is a perspective view of two-part conduits assembled with the base members of an L and of butt coupling fittings, the fitting caps being shown above the bases in positions to be laterally applied thereto; Figs. 2, 3, 4 and 5 are transverse sections indicated, respectively, by the lines II-II, III-III, IV-IV and V-V, Fig. 1, the caps being applied to the bases; Figs. 6 and 7 longitudinal sectional views indicated, respectively, by the lines VI-VI and VII-VII, Fig. 1; Fig. 8 a plan view of a T-fitting assembled with two-part conduits, the modifications necessary to enlarge the T to a cross-fitting being indicated by dotted lines; Fig. 9 a sectional view taken on the line IX-IX, Fig. 8; Figs. 10 and 11 are, respectively, plan and side views of the base member of the T-fitting of Fig. 8, while Figs. 12 and 13 are corresponding views of the cap member; Fig. 14 is a plan view of the base member, and Fig. 15 a plan view of the cap member, of a fitting for attaching a molding conduit to an outlet or similar box; Figs. 16 and 17 are left end views of the base and cap fitting members shown, respectively, in Figs. 14 and 15; Fig. 18 is a sectional view taken on the line XVIII-XVIII, Fig. 14, the cap of Fig. 15 being assembled with the base of Fig. 14, and a single-piece molding conduit being shown 45 assembled with the fitting; Figs. 19 and 20 are plan views, respectively, of base and cap fitting members similar to those shown in Figs. 14 and 15; Fig. 21 is a side-view of the fitting cap of Fig. 20; Fig. 22 a sectional view taken on the line XXXII-XXII, Fig. 19, the cap of Figs. 20 and 21 being assembled with the base of Fig. 19 and with a single-piece conduit; Fig. 23 a side view of an internal elbow assembled with conduits; Fig. 24 a combined sectional and face view taken in the general plane indicated by the line XXIV-XXIV, Fig. 23; and Fig. 25 a sectional view taken on the line XXV-XXV, Fig. 24.

60 While, in the practice of the invention, various shapes and types of conduits may be used, the conduits preferably used are substantially elliptical in cross-section. The two-piece conduit preferably used is of the

form shown in Figs. 1 and 2, and comprises a base 1 of substantially semi-elliptical shape having inwardly turned edges 2, and a cap 3 adapted to rest upon such edges. To hold the cap to the base, spring clips 4, such as shown in Figs. 1 and 5, may be snapped around the assembled base 1 and cap 3 at suitable intervals, such clips being provided with inwardly turned edges adapted to grip the side walls of the base 1. As will presently appear more fully, the clips 4 may also be used as caps for the butt-joint fittings. Longitudinal and cross-sectional views of the single-piece conduit 6 which may also be used are shown, respectively, in Figs. 18 and 22. It will be observed of the 75 two-piece conduit 1, 3 that its outermost points lie in the contour of the outer wall of the single-piece conduit 6, thus making it possible to use such conduits interchangeably with the fitting.

The two-part fittings used in conjunction with the conduit are so constructed that the electrical bonding of the conduits to the fitting bases must precede the assembly attachment of the fitting caps to such bases. In the 80 illustrative embodiment of the invention a single means is provided for the mechanical and the electrical bonding attachments of conduits and fitting bases, the same preferably comprising a pair of spring arms 7 85 between which the conduit may, by lateral pressure, be snapped. While various means may be used for attaching the fitting caps to their bases, it is preferred that they be indirectly attached, as by attaching them to the 90 conduits after the conduits have been attached to the bases. For this purpose the caps are preferably provided with spring arms 8 similar to the arms 7 of the bases.

Referring particularly to the L-fitting 105 shown in Fig. 1, it will be seen that the spring arms 7 are spaced from the main body portion of the base. Specifically, they are formed at the ends of the base. Adjacent to such arms (and connecting them 110 to the central or main body portion 9 of the base) there are tongues 10 which are slightly longer than the width of the cap arms 8, whereby to provide spaces for such arms. It will be readily understood that, in 115 making installations of metal molding thus constructed, it becomes necessary, in order to attach the cap 11 to the base, to have a portion of the end of the conduit 1, 3 (or at least the base portion 1) projecting beyond 120 the inner edges of the arms 7 to receive the arms 8. That is to say, unless the conduits do thus project beyond the edges of the arms 7 and overlap a portion of the tongues 10, the cap arms 8 cannot engage the conduits 125 and hence cannot be assembled in their contemplated operative relation with the bases.

As shown in Figs. 1 and 2, the conduit

1, 3 at the left end of the base fitting extends substantially to the side wall edges 12 of the central portion 9. While it is desirable that the conduits be cut to such lengths that 5 this neat fit may be attained, the conduits may overlap the tongues 10 but a short distance beyond the inner edges of the arms 7, as indicated at the right end of this fitting. Preferably, the bottom and side walls of 10 the central portion 9 and the top and side walls of the central portion 11 of the cap are, as indicated in Fig. 6, so formed that they provide a conductor passageway of substantially the same interior form as the 15 conduit 1, 3, thus eliminating abrupt abrading edges or corners, and forming stops for the ends of the conduits.

In Fig. 1 there is also shown a butt-coupling fitting for connecting and bonding 20 adjacent ends of conduits lying in the same general straight line. The base member of this coupling comprises a central tongue 10 with adjoining spaced pairs of spring arms 7 adapted to engage the conduits and electrically bond them together. The spring 25 clip 4 is used as a cap for this fitting and is assembled with the base by being snapped upon the ends of the conduits 1, 3 between the spaced pairs of arms 7. The conduits, 30 as already explained, must have the full intended electrical bond with the arms 7 before the conduits will overlap the tongue 10 sufficiently to afford points of engagement for the spring clip of cap 4 with both conduits.

Figs. 8 to 13, inclusive, show the assembly and details of the bases and cap members of a T-fitting, wherein the bonding of the fitting base with the conduits, and the 40 assembly of the fitting members is effected in the same manner and with the same advantages as fully described and explained with reference to the fittings of Figs. 1 and 7, inclusive. The base member, shown particularly in Figs. 10 and 11, is provided 45 with three pairs of conduit connecting and bonding spring arms 7 spaced from the main body portion of the base, and the cap, shown in detail in Figs. 12 and 13, is provided with similar arms 8 which engage the conduits at points nearer their ends than do the arms 7. Because T-fittings are usually 50 used at junctions of conductors, the top 13 of the cap is bulged outwardly to afford 55 space for the necessary insulation wrapping at the junction. As already explained, the dotted upper portion of Fig. 8 indicates the modification of form necessary to make a cross-fitting of the same general construction as the T-fitting shown in full lines.

In Figs. 14 to 18, inclusive, there is shown a fitting for connecting a conduit to an outlet or junction box, and the like. As indicated, the outer end of the base member is

provided with a pair of arms 7 for engaging a conduit and bonding it with the box 65 14; while the cap is attached to the base through the engagement of the conduit 6 by the cap spring arms 8. For attaching the inner end of the base member to the box, 70 such end is provided with outwardly curved spring arms 15 adapted to engage the walls of the box adjacent to the opening therethrough. The shape of these arms is such that the fitting may be used either with the 75 round box shown in full lines or with a box having a plane faced wall as indicated in dotted lines at 16. In a similar manner the cap of this fitting is also provided with outwardly curved arms 15^a for engaging the 80 box walls when the several parts are assembled.

The fitting of Figs. 14 to 18, just explained, is intended to be used when the box opening is of the required size to receive the 85 molding to be connected to the box. It is sometimes desirable to connect small two-wire molding to a box provided with large openings for four wire molding. For this purpose the attaching and bonding fitting 90 may be constructed as shown in Figs. 19 to 22, inclusive. This fitting differs from that just explained only in that the base member is provided with a slotted tongue 17 whereby the base may be attached to a box 95 20; while in a similar manner the inner end 100 of the cap of this fitting is provided with a wing 21 to fill the upper otherwise unclosed portion of such opening.

In Figs. 23, 24 and 25 there is shown an internal elbow for connecting and electrically bonding conduits lying in different planes and disposed at an angle to each other. Such fittings are frequently used at corners formed at the junction of two walls or of a wall and ceiling. It is only necessary to explain with respect to this fitting that the base member 22 is provided at its outer ends with pairs of spring arms 7 for mechanically connecting and electrically bonding the two conduits 1, 3, and that the 105 cap 23 is also provided with two pairs of spring arms 8, which, for the purpose of assembling the cap with the base, engage the ends of the conduits 1, 3 at points nearer the ends of the conduits than the conduit-engaging points of the arms 7. It will be readily understood that an external elbow 110 may be similarly constructed.

It will be observed of all the fittings specifically shown and described that they 125 are so constructed that the complete assembly of the cap with the base cannot be effected before a complete and adequate elec-

trical bond has been established between the conduits and fitting bases, and this for the reason that no means are provided whereby the cap member can be attached to 5 the base unless the conduit is in its proper position on, and bonded with, the base. Furthermore, either one or two-piece conduits may be used with the fittings, and both may be connected to the fitting bases by 10 general application rather than by sliding the conduits longitudinally.

According to the provisions of the patent statutes we have described the principle and 15 operation of our invention and have explained in detail the construction of the metal molding which we now consider to represent the best embodiment thereof. However, we desire to have it understood that the invention may be practised by 20 other forms of molding than that particularly shown and described.

We claim as our invention:

1. The combination with a conduit base 25 for electrical conductors, of a conduit fitting comprising a base and cap assembled with said conduit base, said conduit base and fitting base being constructed of electrical conducting material and having overlapping current-transmitting contact faces, 30 complete electrical bonding contact between said conduit base and fitting base being requisite to effect complete assembly of said cap with said fitting base.

2. The combination with a conduit base 35 for electrical conductors, of a conduit fitting comprising a fitting base provided with means for attaching and electrically bonding it to said conduit base, said conduit base and fitting base being constructed of 40 electrical conducting material and having overlapping current-transmitting contact faces, and a cap provided with means for attaching it to said conduit base, the cap-attaching means being ineffective for such 45 purpose prior to the attachment and bonding of the fitting base to said conduit base.

3. The combination with a conduit base 50 for electrical conductors, of a conduit fitting comprising a base and a cap, said conduit base and fitting base being constructed of electrical conducting material and having at their points of assembly current-transmitting faces, said fitting base being 55 provided with means for electrically bonding it with said conduit base, and said cap having means for mechanically attaching it to said conduit base, said bonding and said cap attaching means being spaced with relation to each other and longitudinally of 60 said conduit base whereby the cap-attaching means may engage said conduit base when and only when the conduit base is fitted to said bonding means of said fitting base.

4. The combination with a conduit base

for electrical conductors, of a conduit fitting comprising a base and a cap each having means gripping said conduit base, said conduit base and fitting base being constructed of electrical conducting material and having current-transmitting faces at the gripping point of the conduit base by the fitting base, the gripping means of the cap being spaced with relation to the gripping means of the fitting base and longitudinally of 70 said conduit base whereby the gripping means of the cap may engage the conduit base when and only when the conduit base is engaged by the gripping means of the fitting base.

5. The combination with a conduit base 75 for electrical conductors, of a conduit fitting comprising a base and a cap, said conduit base and fitting base being constructed of electrical conducting material and having at their point of assembly current-transmitting faces, the fitting base including a main body portion and means spaced therefrom gripping said conduit base, and said cap being provided with conduit-gripping means effective to engage said conduit base only when a portion thereof lies in the space between the main body portion and conduit gripping means of said fitting base.

6. In a metal molding installation, the 80 combination of a pair of conduit bases having their ends adjacent to each other, and a fitting comprising a base having a pair of conduit-gripping means each engaging an end of said conduit bases, said conduit bases and fitting base being constructed of electrical conducting material and having current-transmitting faces at the gripping points of the conduit bases by the fitting base, said means being spaced apart and the 85 ends of the conduit bases lying in such space, and a cover engaging said conduit bases between the points of engagement of the conduit-gripping means of said fitting base.

7. The combination with a conduit base 90 for electrical conductors, of a conduit fitting comprising a base and a cap, said conduit base and fitting base being constructed of electrical conducting material and said fitting base receiving and making overlapping electrical contact with said conduit base, said cap being applied to said fitting base and secured thereto solely by engagement with said conduit base and only after the 95 conduit base has been received by and brought into electrical contact with said fitting base.

8. The combination with a conduit base 100 for electrical conductors, of a fitting including a base provided with arms engaging said conduit base and forming an electrical bond therewith, said conduit base and fitting base being constructed of electrical conducting material, and a cap provided with arms 105

engaging said conduit base at a point nearer to the end thereof than the point of conduit engagement of said fitting arms, said cap and fitting base being connected to each other solely through the engagement of their respective arms with said conduit base.

9. The combination with a conduit base for electrical conductors, of a fitting comprising a base provided at one end with a single means for the attachment and electrical bonding of said conduit base thereto, said conduit base and fitting base being constructed of electrical conducting material and having at their point of assembly current-transmitting faces, and a cap for said

fitting base provided with means for engaging said conduit base, said conduit-engaging means of the cap being, in the assembly of conduit base, cap and fitting base, effective only after the attachment and electrical bonding of said conduit base and fitting base by the aforesaid means therefor.

10. In a metal molding installation, the combination of a fitting base provided at its outer end with arms for receiving a conduit base for electrical conductors and at its bottom with a tongue extending from the inner edges of said arms, a conduit base engaged by said fitting base arms and having a portion of its end overlapping said tongue, said conduit base and fitting base being constructed of electrical conducting material and having at their point of assembly current-transmitting faces, and a cap provided with means for engaging said overlapping portion of the conduit base.

11. In a metal molding installation, the

combination of a fitting base provided at its outer end with arms for receiving a conduit base for electrical conductors, and at its bottom with a tongue extending from the inner edges of said arms, a conduit base engaged by said fitting base arms and having a portion of its end overlapping said tongue, said conduit base and fitting base being constructed of electrical conducting material and having at their point of assembly current-transmitting faces, and a cap provided with arms engaging said overlapping portion of said conduit base.

12. The combination with a conduit base for electrical conductors, of a conduit fitting comprising a base and a cap, said conduit base and fitting base being constructed of electrical conducting material, said fitting base being provided with means for effecting electrical bonding connection with said conduit base, and said cap being provided with means for mechanically attaching it to said conduit base, the effecting of said bonding connection between said conduit base and fitting base being, in the complete assembly of cap, fitting base and conduit base, a requisite to the effecting of said mechanical attachment of said cap to said conduit base.

In testimony whereof we have hereunto set our hands.
